UNITED STATES PATENT OFFICE.

JOSEPH HILBERT, OF DUSSELDORF, GERMANY.

DOCUMENT-FILE.

SPECIFICATION forming part of Letters Patent No. 653,239, dated July 10, 1900.
Application filed February 20, 1899. Serial No. 706,163. (No model.)

To all whom it may concern:

Be it known that I, JOSEPH HILBERT, a citizen of the German Empire, and a resident of Dusseldorf, Germany, have invented certain new and useful Improvements in Document-Files or Portfolios, of which the following is a specification.

This invention relates to a document-file which can be held either in a distended position to constitute a shelf or may be contracted and folded to constitute a portfolio.

In the accompanying drawings, Figure 1 is a side elevation of my improved document-file, showing it distended; Fig. 2, an end view thereof; Fig. 3, an end view showing the file collapsed; and Fig. 4, an enlarged side view, partly in section, of one of the hinged frame-bars *s*.

The letters *a a* represent a number of superposed flexible bellows open at one or both ends and provided with partitions *a'*, which constitute shelves. To the upper and lowermost bellows *a* are secured heads or covers *d*, provided with eyes *o*. These eyes are adapted to be removably engaged by pins *m*, projecting laterally from the ends of a pair of rigid upright frame-bars *s*, which are made folding by being provided with a central hinge *s'*.

When the file is to constitute a shelf, the pins *m* are brought into engagement with the eyes *o* to hold the bellows *a* in a distended position and permit documents, letters, &c., to be placed upon the partitions *a'* in the compartments.

When the file is to constitute a portfolio, the pins *m* are withdrawn from the covers *d* and the bars *s* are removed, so that the bellows *a* will collapse. In this condition the bellows may be closed by a lock, fastener, or flaps *k*.

What I claim is—

A file composed of a series of superposed flexible bellows having partitions, covers secured to the upper and lowermost bellows, eyes on the covers, folding upright frame-bars composed of a pair of hinged sections, and pins that project laterally from the ends of the frame-bars and are adapted to removably engage the eyes, substantially as specified.

Signed by me at Dusseldorf, Germany, this 7th day of February, 1899.

JOSEPH HILBERT.
